UNITED STATES PATENT OFFICE.

HENRY A. RIDDLE, OF CHAMBERSBURG, PENNSYLVANIA, ASSIGNOR OF
ONE-FOURTH TO JOHN S. KENNEDY, OF SAME PLACE.

RAILWAY-TICKET.

SPECIFICATION forming part of Letters Patent No. 544,052, dated August 6, 1895.

Application filed February 21, 1895. Serial No. 539,169. (No model.)

To all whom it may concern:

Be it known that I, HENRY A. RIDDLE, a citizen of the United States, residing at Chambersburg, in the county of Franklin and State 5 of Pennsylvania, have invented certain new and useful Improvements in Railway-Tickets, of which the following is a specification.

My invention relates to railway-tickets designed particularly for use by railway companies in meeting the suburban competition of electric and cable lines without interfering with the established tariff rates of the company.

In the drawings, Figure 1 is a front face 15 view of my ticket in its preferred form; Fig. 2, a rear face view; Figs. 3 and 4, views with the book or ticket open; and Fig. 5, a view showing the application of my invention to a card-ticket.

20 In the preferred form of my invention the ticket will be bound like a book—that is to say, it will comprise the front A, back B, and leaves C and D, suitably bound together.

On the outer face of the cover-section or 25 front A is placed the name or title of the ticket and a place for the agent's stamp. On the reverse face of said cover-section or front A is a space for the patron's name, and also a space for the insertion of the time limit. 30 Below this is a space for the name of the place of sale, and the number "599" of the ticket, each ticket of course being provided with a separate and distinctive number.

On the inner face of the cover-section or 35 back B is the usual contract to be signed by the commuter and a place for such signature, and below this is the last coupon a, numbered "50" to correspond with the number of coupons in the book, and bearing also the form- 40 number "50's," the ticket-number "599," and instructions to the effect that the coupon is good, if not detached, for passage for a distance of three miles or less between points east of and including "Carlisle."

45 The leaves C are made up of a series of coupons b, similar in all respects, except that they are numbered consecutively from 2 to 49, inclusive, and said coupons contain sub- 50 stantially the same subject-matter as that found on the last coupon a, just above referred to.

There are six coupons on a page, separated by perforations or indentations, and as there are eight pages in the book-ticket illustrated, there will be forty-eight coupons on said leaves C. Of course the number of coupons and leaves and the distribution and arrangement of the coupons upon the leaves is a matter that may be varied, as desired. 55

The first leaf D contains the auditor's check 60 and also the first coupon c, which check and coupon, comprising substantially the entire leaf, is to be detached by the conductor on the first trip made by the commuter and returned to the auditor. This auditor's check 65 contains the number "599" of the ticket, and space for commuter's name, date of sale, and name of agent to whom ticket is to be charged.

The coupon c is similar to the coupons a b, 70 before referred to, except that it is numbered "1," showing that it is the first of the series of fifty coupons constituting the ticket.

On the rear face of the back or cover section B is a table showing how many coupons 75 are to be detached for a ride between any two points covered by the ticket.

There are names d of the stations, and in line therewith numbers e in bold-faced type, by which the stations are indicated or designated. 80 This row of numbers e extends across the back and is supplemented by a vertical row of corresponding numbers e'. Lines f, extending vertically and horizontally between the respective numbers e e', form squares or spaces 85 g, in which are placed numbers h, preferably printed in light-faced type, which indicate the number of coupons to be detached for passage between stations whose respective numbers are in the intersecting columns. For 90 instance, in going from Harrisburg to White Hill, one coupon will be taken up; from White Hill to Middlesex, five coupons, or from Harrisburg to Carlisle, seven coupons. This number of coupons to be taken up is determined— 95 say, for example, in going from Harrisburg to White Hill—as follows: Run down the second column (in which Harrisburg appears) until opposite the number "3," the White Hill station-number, in the first column, and 100 the light-faced number "1" will be met, thereby indicating that one coupon is to be taken

up; or, in going from White Hill to Middlesex, run down the fourth column until opposite "14," the station-number of Middlesex, and where these two columns or rows intersect 5 would be found the number "5," showing that five coupons should be collected.

The light-faced number at the intersection of any two columns headed by the station-numbers indicates the number of coupons to be collected for passage between the stations whose numbers are considered.

From this table the commuter, as well as the conductor, can determine how many coupons should be taken up, thereby avoiding the computations and disputes arising from the use of mileage-tickets. The present invention is, however, not intended to take the place of the mileage-tickets in common use, but to place in the hands of commuters a ticket similar to those used by street-railway companies, except that it is limited in time and restricted to use by certain persons, thereby providing the commuter with a ticket good to or from any one or more of a number 25 of stations between certain points and avoiding the delay incident to the purchase of tickets.

By the purchase of this ticket suburban patrons have the advantage of a low rate in 30 the shape of time-limited commutation-tickets, the use of which can be confined to any desired territory. At the same time this form of ticket is of no advantage to through passengers from whom the regular rates can be 35 collected.

Instead of station-numbers, other distinctive marks may be used—such, for instance, as letters. It is also apparent that the matter on the cover-sections A B may be trans- 40 posed, if desired; but the arrangement which I have shown and which has been in successful use for some time is preferred.

The invention may obviously be applied to that style of commutation-tickets known as 45 the "card-ticket," which, instead of having detachable coupons, is provided with numbered spaces to be punched by the conductor.

My ticket combines with the best features

of the commutation-ticket the further advantage that instead of being good only between two fixed points at a given rate, is good between any points in the territory specified, each coupon, if of coupon-form ticket, or each number to be punched, if of card form, to be good for one ride of three miles or less, (the usual maximum distance for tramway-car fares,) and the number of coupons to be detached, or numbers punched, being governed by the distance traveled and readily determined by reference to the table forming a part of the ticket.

The expression "Good for one ride of three miles or less," is used simply for the purposes of illustration, as the maximum distance corresponding to one coupon; but the limitation will be varied to suit the interests of the parties concerned.

The ordinary mileage-ticket and the ordinary commutation-ticket have not proved satisfactory in meeting the competition of sub- 70 urban electric and cable railways, as they fail to provide a limited ticket at a reduced rate, good between any points in a given territory.

In Fig. 5 I have shown my invention as applied to the ordinary form of card commutation-ticket in which, instead of having detachable coupons, there are the equivalents thereof—numbers or figures to be punched out by the conductor.

Having thus described my invention, what I claim is—

The herein described ticket, comprising a series of coupons; an auditor's stub having the first of said coupons permanently united thereto so as to be collected therewith; and a leaf or page containing a table to be used in connection with the coupons, and containing the last of the coupons, all substantially as shown.

In witness whereof I have hereunto set my hand in the presence of two witnesses.

HENRY A. RIDDLE.
